ATTORNEY

UNITED STATES PATENT OFFICE.

IRVING EDELMAN, OF BROOKLYN, NEW YORK.

ADVERTISING DEVICE.

Application filed August 3, 1927. Serial No. 210,251.

This invention relates to an advertising device.

In the sale of luxuries such as perfumes, candies and other articles sold in boxes it has been found that attractive boxes enhanced the sale of the product. In most instances there is practically no utilitarian use for the box or lid after it has served its purpose as a container for the article sold.

10 One of the objects of this invention is to provide an attractive box. Still another object of this invention is to provide a box having a lid which can subsequently be utilized as a picture frame, mirror frame or similar purpose.

15 Still other objects of this invention are to provide an attractive container having a utilitarian use to increase the sales of the product sold therein and which can be manufactured 20 at a relatively cheap cost.

Referring to the drawings:

Figure 1 is a top view of a box lid embodying the principles of my invention.

Figure 2 is a sectional view of Figure 1 25 along the line 2, 2, looking in the direction of the arrows and showing in dotted lines its use as an easel picture frame.

Figure 3 is a back view of Figure 1.

Figure 4 is an end view of a box partly in 30 section showing the lid thereon.

Figure 5 is a detailed view of a modification of the structure of the lid.

In carrying out my invention I propose to provide a box 1 formed of sheet metal of 35 the usual construction having a lid 2 therefor. Lid 2 may be made in divers ways and I have shown the preferred form. The bottom of lid 2 is made from a single piece of sheet metal 3. At the ends of sheet 3 are

40 grooves 4 pressed in said sheet 3 to retain the picture in position. Adjacent to grooves 4, sheet 3 is bent to form shoulder 5 to receive the crimped over end 6 of molding 7. Molding 7 is adapted to retain glass 8 and picture 45 9 in the pocket formed in sheet 3 by grooves 4. Molding 7 may either be straight as shown in modified form in Figure 5 or may be curved in conformity to grooves 4 as shown in Figure 2. Sheet 3 also has cutout in the back

50 thereof flap 10. Tongues 11 may also be cutout and pressed in to hold the picture 9 and glass 8 against molding 7. Molding 7 may have a design placed thereon in any well known manner such as by lithographing etching, etc. and may also have thereon a trade-

mark to advertise the contents of the box. If it is desired a hole 12 may be placed in the back of sheet 3 in order that the lid may be utilized as a frame to be hung on a nail.

The purchaser of the container may when 60 the contents have been removed replace the picture or advertising matter with one of his own by sliding the one already in the box out of the lid through slots 13 in lid 2 and insert a new picture together with the glass. 65 The purchaser then has a framed picture which he can hang up by means of hole 12 or by bending back flap 10, lid 2 will function as an easel frame.

It will thus be seen that I have invented an 70 advertising device which can be utilized as a picture frame or for many other purposes. The cost of manufacture is but little more than the present box lids for metallic boxes and the seller by utilizing his trademark thereon 75 has an opportunity to advertise it if the purchaser makes use of the box lid for the purposes for which it is designed.

What I claim is:

1. In combination with a box, a lid, said lid 80 having a back plate of a single piece of sheet metal and a front plate having a central display opening, the back plate having grooves formed therein near the edges, the material of the bottom of the grooves bearing against the front plate adjacent the edges of the display opening, the material of the back plate between the grooves forming the bottom of a recess for receiving display members behind the display opening in the front plate, the inner edges of the display opening overlapping 85 said recess, tongues struck out of the back plate to bear against display members in the recess, the outer edges of the front plate being crimped over those of the back plate, and shoulders formed in the back plate between the grooves and the outer edges to fit the edges 90 of the box.

2. In combination with a box, a lid, said lid 100 having a back plate of a single piece of sheet metal and a front plate having a central display opening, the back plate having grooves formed therein near the edges, the material of the bottom of the grooves bearing against the front plate adjacent the edges of the display opening, the material of the back plate between the grooves forming the bottom of a recess for receiving display members behind the display opening in the front plate, the inner edges of the display opening 105 110

overlapping said recess, tongues struck out of the back plate to bear against said display members in the recess, a flap portion struck out of the back plate and adapted to be bent back for a support, the outer edges of the front plate being crimped over those of the back plate, and shoulders formed in the back plate

between the grooves and the outer edges to fit the edges of the box.

Signed at New York, in the county of New ¹⁰ York, and State of New York, this 28th day of July A. D. 1927.

IRVING EDELMAN.
